Fig. 6.

Inventor
Harold S. Neiman

UNITED STATES PATENT OFFICE.

HOWARD S. NEIMAN, OF BROOKLYN, NEW YORK.

WIND-SHIELD.

1,269,634.

Specification of Letters Patent. Patented June 18, 1918.

Application filed February 23, 1917. Serial No. 150,314.

To all whom it may concern:

Be it known that I, HOWARD S. NEIMAN, a citizen of the United States, and a resident of the borough of Brooklyn, in the county of 5 Kings, city of New York, and State of New York, have invented certain new and useful Improvements in Wind-Shields, of which the following is a specification.

My invention relates to windshields and 10 refers particularly to windshields suitable for use upon automobiles.

In order that windshields of this character may be useful in all kinds of weather, they are pivotally attached to a supporting 15 standard to allow of their being opened or closed as desired, such pivotal means being situated at the upper portion of the shield in order that it may be revolved inwardly and upwardly to a horizontal position, the 20 position of the steering-wheel being such that it can not be revolved inwardly and downwardly from its lower position.

One great disadvantage of the present employed windshields is that when in a partially 25 opened position, rain and wind are deflected downwardly upon the lower limbs of those sitting upon the front seats, thus causing inconvenience and discomfort.

My invention overcomes this difficulty and 30 at the same time allows the windshield to be revolved inwardly and upwardly out of the way when desired.

In a broad way my invention comprises a windshield so pivoted that it may be revolved either inwardly and upwardly or inwardly and downwardly, thus accomplishing all of the objects of the present employed windshields, with the additional valuable 35 property of protecting the occupants of the vehicle.

Modified forms of my invention are illustrated in the accompanying drawings, in which similar parts are designated by similar letters and numerals.

Figure 1 is a broken front view of one 45 form of my invention partly broken away to disclose the pivotal means.

Fig. 2 is a sectional view of the windshield shown in Fig. 1.

Fig. 3 is an enlarged end view of a portion of Fig. 1 showing the means employed for allowing the windshield to revolve past the pivotal means.

Fig. 4 is a side view of Fig. 3.

Fig. 5 is an end view of a modified form 55 of my invention applied to a closed vehicle.

Fig. 6 is an enlarged top plan view of a portion of Fig. 5, showing the pivotal means.

In the form of my device illustrated in Figs. 1, 2, 3 and 4, the two wind shields A 60 and B, comprised respectively of the frame 7 and the transparent medium 8, and the frame 9 and the transparent medium 10, are situated between the supports 11, 11. The supports 11, 11 have a number of threaded 65 holes, 12, 12, 12, 12. Through each one of the said threaded holes is inserted a threaded binding member comprised of the threaded bar 13, capable of enmeshment with the threads of the hole 12, the interior end of 70 the bar 13 carrying an annular disk 14, integral therewith, said disk 14, having an extended pin 15. The exterior end of the bar 13 has an annular member 16, integral therewith. Within the windshield frames 7 and 75 9 is a recess 17, capable of receiving the member 14 of the binding member, the annular recess 17 being extended inwardly into a smaller annular recess 18 capable of receiving the pin 15 of the binding member. 80 The recess 17 is of such a shape, as illustrated in Fig. 3, that the frame 7 may be revolved from engagement with the member 14. The steering wheel is represented at S.

The method of operating the windshield 85 A is as follows:—The two upper binding members are screwed inwardly until their pins 15, 15 are inserted within the recess 18 of the frame 7, the annular member 14 of the binding member not being brought into 90 contact with the surface of the recess 17, thus allowing free movement of the windshield A upon the pins 15, 15 as pivots. The two lower binding members are then screwed outwardly until their pins 15, 15 are entirely 95 removed from the recesses 18, 18 of the frame 7. The windshield is then free for revolution upon the upper pins 15, 15 as shown in A¹ and A² of Fig. 2. When the windshield A is in the desired position, the 100 two upper binding members are screwed inwardly until the faces of the members 14, 14 are frictionally engaged with the surface of the recesses 17, 17, thus maintaining the windshield in the desired position.

When it is desired to revolve the windshield A upon its two lower pivots into the positions A³ and A⁴ of Fig. 2, it is revolved back into its upright position, the two lower pins 15, 15 are screwed into the two lower recesses 110 18, 18, the two upper pins 15, 15 are released from their insertion within the two upper

recesses 18, 18, and the windshield manipulated upon the two lower pivots as above described. By having the space between the frame 7 and the supporting member 11 less than the thickness of the annular member 14, there is no danger of the accidental dropping of the shield from the support, as the member 14 will always act as a support for the frame 7, even when screwed out to its 10 farthest position.

It is evident that when the windshield is in a position pivotal from its upper bearings as A¹, the wind or rain entering the vehicle is deflected downwardly upon the feet of the 15 driver, whereas when it is pivotal from its lower bearings in the position as A⁴, the wind or rain will be deflected upwardly, thus protecting the driver and rain will run downwardly from the shield outside the vehicle.

20 Figs. 5 and 6 illustrate a modification of my device, particularly suitable for closed vehicles, and is so constructed that all of the operating members are within the vehicle.

25 Fixedly attached to the frame 7 are brackets 19, 19, while fixedly attached to the side 20 of the vehicle are brackets 21, 21. The threaded bar 22, extends through the hole 23 of the bracket 19 and the hole 24 of the bracket 21. A sleeve comprised of the 30 tubular member 25 and the annular disk 26, surrounds the bar 22, extending inwardly into the hole 23 and is capable of revolution around the bar 22. The sleeve 25 is of a square form externally to fit within the 35 square shaped interior of the bracket 19 so as to prevent the revolution of the bracket 19 around the sleeve 25, but to allow of its 40 slideable movement thereon. Upon one end of the bar 22 is fixedly attached a disk 27 carrying an inwardly extended pin 28, capable 45 of insertion in the recess 29 of the bracket 21. Situated between the threaded bar 22 and within the hole 23 of the bracket 19 is an interiorly threaded nut 30. A series of four mechanical constructions such as above described is situated between the 50 windshield and its support in a manner similar to that shown in Fig. 1.

55 The operation of the modification illustrated in Figs. 5 and 6 is as follows: If it is desired to revolve the windshield upon its two lower pivots, the two lower nuts 30, 30 are screwed inwardly, thus causing the bar 22 to move outwardly until the pins 28, 28 60 of the members 27, 27 enter the recesses 29, 29 of the brackets 21, 21, thus pivotally locking the frame 7 to the side 20 of the vehicle. The two upper nuts 30, 30 are then 65 screwed outwardly, causing the two upper bars 22 to move inwardly until the two upper pins 28, 28 are completely disengaged with the two upper recesses 29, 29, thus disconnecting the upper portion of the frame 7 from engagement with the side 20 of the vehicle, and allowing free revolving movement

70 to the upper portion of the windshield. When the shield has been revolved to its desired position, the two lower nuts 30, 30 are further screwed inwardly, the inner portion of the nuts 30, 30 bearing upon the member 25, forcing it inwardly until the surface of the member 26 abuts upon the surface of the bracket 21, thus frictionally holding the shield in position.

75 When it is desired to revolve the windshield upon its two upper pivots, the above operation is reversed as to the two series of pivotal and binding members.

80 In vehicles of this class, an additional windshield C, is frequently placed outside to act as a deflector of rain and is intended as a means of producing a clear vision by causing said additional shield to operate as a means for maintaining the actual windshield in a condition free from moisture. In order to accomplish this, the windshield C must be placed in a position somewhat as shown in Fig. 5.

85 It is evident that when the windshields are in the positions C and A⁵ of Fig. 5, that 90 rain and wind will be deflected downwardly upon the driver of the vehicle, whereas, when they are in the positions C and A⁶, the wind will be deflected upwardly above the driver and that rain accumulating upon the windshield A⁵ will run downwardly outside of 95 the vehicle, thus causing a valuable protection to the driver and the interior of the car.

I do not limit myself to the particular 100 size, shape, number or arrangement of parts, all of which may be varied without going beyond the scope of my invention as described and claimed.

What is claimed, is:

1. In a device of the character specified, 105 in combination, a support, a windshield, means connecting the support and the windshield and allowing the revolution of the windshield upon two axes of revolution at opposite sides of the windshield and means 110 between the windshield and the support for maintaining the windshield at any predetermined position of revolution.

2. In a device of the character specified, 115 in combination, a support, a windshield, two 120 series of pivotal means at approximately the top and bottom of the windshield around each of which series the windshield may be revolved, and frictional means between the windshield and the support for maintaining the windshield at any predetermined position of revolution.

3. In a device of the character specified, 125 in combination, a support, a windshield, removable pivotal means between the windshield and the support upon which the windshield may be revolved at approximately its upper edge and approximately its lower edge and frictional means between the pivotal member and the windshield for 130

supporting the windshield at any predetermined position of revolution.

4. In a device of the character specified, in combination, a support, a windshield, a series of two pivotal means at approximately the top of the windshield, a series of two pivotal means at approximately the bottom of the windshield, each pivotal means comprising a removable pivot, where-
10 by the windshield may be removed from pivotal engagement with the support, allowing free revoluble movement of the windshield and means operative with the pivotal means for maintaining the wind-
15 shield at any predetermined position of revolution.
5. In a device of the character specified, in combination, a support, a windshield, a series of two pivotal means at approximately the top of the windshield, a series of two pivotal means at approximately the bottom of the windshield, each pivotal means comprising a pivot movably carried by the support and capable of pivotal at-
20 tachment with the windshield, means car-
25 ried by said pivot to maintain the wind-
shield in any predetermined position of revolution, and means for removing the pivot from engagement with the windshield and means for allowing a revoluble move-
30 ment of the windshield.
6. In a device of the character specified, in combination, a support, a windshield, a series of two pivotal means at approximately the top of the windshield, a series of two pivotal means at approximately the bottom of the windshield, each pivotal means comprising a threaded bolt, means whereby the turning of said bolt upon its threads will first place the support and windshield in
35 pivotal engagement, a further movement of the bolt locking the support and windshield into non-movable engagement, and means whereby the turning of said bolt in an op-
posite engagement will release the wind-
40 shield from engagement with the support.
45

Signed at New York city, in the county of New York and State of New York, this 21st day of February, 1917.
